J. BAUMAN.
CIDER MILL AND PRESS.

No. 11,151.

Patented June 27, 1854.

UNITED STATES PATENT OFFICE.

JESSE BAUMAN, OF SHEPHERDSTOWN, PENNSYLVANIA.

CIDER-MILL.

Specification of Letters Patent No. 11,151, dated June 27, 1854.

To all whom it may concern:

Be it known that I, JESSE BAUMAN, of Shepherdstown, in the county of Cumberland and State of Pennsylvania, have invented a new and useful Improvement in Cider-Mills; and I do hereby declare that the following is a full, clear, and exact description of the same, reference being had to the accompanying drawings, making part 10 of this specification, in which—

Figure 1 is an elevation; Fig. 2, a top view of the grinding plate, the top of the machine removed; Fig. 3, a portion of the top of the machine; Fig. 4, a section of the 15 secondary mill.

The nature of my improvement consists, first in so constructing a mill for grinding apples, that it shall perfectly reduce them to a pulp (a condition absolutely required to 20 make the most cider out of a given quantity of apples,) and freely receive the feed from the hopper, and retain the apples between the grinding surfaces without the necessity of previous slicing required in other mills to 25 secure that object, and secondly in so arranging the pressing with the grinding apparatus, that the production of cider may be completed at one operation, and requiring no other attention than that the supply 30 should be kept up in the hoppers, thus avoiding a vast amount of labor in handling the soft pomace in subjecting it to a press in large quantities, to say nothing of the impurities consequently arising without great 35 care. This mill is equally applicable to grinding peaches.

To enable others skilled in the art to construct and use my invention I will describe the construction and operation of the mill 40 and press.

In the drawings the representation is of one adapted to horse power although it is equally applicable to a hand machine, particularly, when the grinding portion is 45 constructed as represented in the secondary mill.

In a suitably constructed frame is placed the vertical driving shaft A on which the sweep is secured. This shaft carries a bevel 50 wheel gear B actuating the secondary grinding mill or cylinder.

C, C, is a horizontal grinding wheel or plate, secured on A, its upper surface divided into four planes, the ridges *a*, thereof 55 radial from the shaft A and the planes declining toward *d*. These planes are fur-

nished with spikes or teeth for rasping the fruit.

D, D, (in dotted line Fig. 1,) are springs secured on the underside of the top of the machine, and are for the purpose of keeping the apples in contact with the teeth and planes of C, C, being provided with a shoulder for retaining the fruit until reduced to a pulp or pomace.

E, E, Figs. 1 and 3, are holes for the apples, to pass from a hopper placed on the top of the machine; F F, a hoop surrounding the rasp or grinding wheel, for retaining the pomace and delivering it through G, 70 into the pressing box H, by an opening I therein; K, a piston working in H, and connected with the pivoted arm M; e, a friction roller in contact with the outer face of a cam L (on shaft A) and *d* is a bent 75 rod in contact with the inner face of the cam, both are secured to the arm M; N, is the pomace drawer formed with flutes or hollows into which the pomace is compressed by the action of the piston K. It is retained 80 in its place by a strong spring O.

The operation is as follows: The apples being received from a hopper, through openings E, E, are retained against the wheel C, C, until perfectly reduced to a pulp, the 85 spring and plate thereof retaining them in contact, yet permitting the planes *a*, *b*, to pass. When the fruit is sufficiently ground (which is important) it is thrown off the wheel or plate *c c* by centrifugal force, and 90 being encompassed by the hoop F F is directed through the opening G and falls into the pressing box H, where it is subjected immediately to the compression of the piston K, actuated by the cam L. When the box 95 becomes sufficiently full of pulp, and the pomace relieved of the fluid the pulp consolidates in the hollows or indents in the pomace drawer N, and the pressure of the cam and piston overcoming by continuous 100 packing, the spring O, (whose use is the retaining the pomace drawer N,) it then gives way and permits the dry pomace to pass out of the box H gradually: and thus a continuous grinding and pressing of the fruit is 105 produced at one and the same operation.

The advantage gained in the grinding apparatus from the use of the springs for holding up the fruit to the rasp-wheel, of keeping up the feed to the work may be adduced; 110 this is not the case in a turning cylinder and concave bed, as in that arrangement the ap-

5 ples are slowly taken hold of by the teeth of the cylinder, and do not enter the concave until considerably reduced in diameter, and then in such quantities as to choke the mill, 10 or make it work hard and irregularly, while by my method of holding up the fruit as on a shelf, it is reduced to a pulp and the mill 15 works regular.

10 The secondary mill or grinder, which may be used by hand when a small quantity of fruit is to be ground, is constructed as follows: P, the cam shaped grinder provided with spikes or teeth on its periphery; Q, a stationary concave bed is provided with 15 teeth; R, the holding up spring to retain the apples until reduced to a pulp. The operation of the mill so nearly resembles the one described as to render unnecessary a further description.

15 20 Having described my improvement in mills for grinding and pressing fruit at one operation, what I claim as my invention and desire to secure by Letters Patent is—

1. The use of the wheel C, C, provided with offsets, or planes *a*, *b*, and teeth or 25 spikes as described in combination with the springs D, D, for grinding the fruit.

2. I claim the arrangement of the grinding wheel C, C, springs D, D, with the cam E, pressing box H, and pomace drawer N 30 and spring O, for the purpose of pressing the pulp, and delivering the pomace, substantially as set forth.

3. And I claim in the secondary mill the arrangement of the spring R, concave Q and 35 cam shaped rasping wheel, or grinder P, for the purpose of reducing the fruit to a pulp.

In testimony whereof I have hereunto signed my name before two subscribing witnesses.

JESSE BAUMAN.
